TWO-REVOLUTION PRINTING PRESS

Paul Dietrich and Emil Kolland, Augsburg, Germany, assignors to Maschinenfabrik Augsburg-Nürnberg A. G., Augsburg, Germany, a corporation of Germany

Application May 12, 1951, Serial No. 225,962

Claims priority, application Germany May 17, 1950

5 Claims. (Cl. 161—250)

This invention relates to a two-revolution printing press of the type in which the reciprocating type bed is driven by a toothed rack, a toothed segment, and a shaft from a toothed segment positioned laterally of the type bed, which toothed segment bears at each end of its toothing an extension with cycloidal recess and is driven alternately by either of two oppositely moved toothed segments at the end of each of which is mounted a roller for alternating engagement in the cycloidal recesses for retarding and accelerating the movement of the type bed. By providing a special ratio between the total swinging period of the toothed segment bearing the cycloidal recesses and the time of engagement of the rollers in the cycloidal recesses it is possible to reduce their retarding and accelerating effect to such an extent that separate retarding and accelerating devices, e. g. in the form of air buffers, can be dispensed with. Therefore, the toothed driving rack can be arranged in the middle plane of the type bed without any difficulties.

However, since in this type of type bed drive the toothed segment comes to lie halfway between the side walls of the machine frame, approximately in the middle of the type bed track, i. e., closely beneath the axis of the impression cylinder defining the impression line in which the very strong pressure forces between the impression cylinder and the type bed are acting, it causes special difficulties to design the main transverse girder of the machine frame in such a way, in the course of the impression line, that it is able to resist the heavy pressure forces without any flexible action. Such possible flexibility, however, is of a decisive importance for the quality of the printing; an absolutely rigid construction of the bearing of the impression cylinder and of the support of the type bed by the main transverse girder of the machine frame in the region of the impression line tends to reduce the amount of work required for making ready the impression cylinder which hitherto owing to the flexibility in the middle of the cylinder had to be more thorough in the middle of the cylinder than outside. The position of the toothed segment for driving the toothed rack of the type bed would not admit of the provision of a continuous upper chord directly beneath the impression line.

It is an object of the present invention to provide a two-revolution printing press which combines maximum stiffness and maximum simplicity of construction.

With this and further objects in view, which will hereinafter appear, according to the present invention a continuous upper girder for the main transverse support is provided and made sufficiently stiff against bending by supporting the tracks for the type bed below the impression cylinder by single vertical stays bearing on the lower chord of a constructional element taking the transverse forces (e. g. a stay or a truss) connecting in a slanting course the lower chord arranged vertically or approximately vertically underneath the impression line and the continuous upper chord extending laterally of the impression line, and forming together with these chords the main transverse girder of the machine frame.

2

The lower chord in this case is advantageously constructed in the form of a horizontal girder for taking the lateral components of the vertical forces and has, for instance, a slightly U-shaped form. A maximum of stiffness is obtained by drawing apart the upper and lower chords as far as possible and arranging them in the upper and lower planes of the frame, respectively.

In this construction of the main transverse girder of the machine frame it does not make any difference that the constructional element interconnecting the upper and lower chords in a slanting direction requires a recess or bulging in the region of the swinging motion of the toothed driving segment.

Other and further objects, features and advantages of the invention will be pointed out hereinafter and appear in the appended claims forming part of the application.

In the accompanying drawings a now preferred embodiment of the invention is shown by way of illustration and not by way of limitation.

Fig. 1 is a side view of the machine,
Fig. 2 is a cross section on the line II—II of Fig. 1, and

Fig. 3 is a fragmentary view of the drive.

Similar reference numerals denote similar parts in the different views.

Referring now to the drawings in greater detail, it will be seen that the sheets coming from the feeding apparatus 1 are fed to the impression cylinder 4 via the feeding table 3 by means of the well known feeding device 2 and taken along by the impression cylinder, whereby the sheet is printed by the matter 6 over which the ink has been distributed by the inking apparatus 5, whereupon the printed sheets are fed to the delivery pile board 8, by the chain delivery 7 having two grippers 58, 58'. The composition 6 is enclosed in a type bed 9 which is supported, by four slide guides 10, in corresponding tracks 11 of the machine frame. Each track 11 rests on vertical supports 12, which in turn are supported on the lower chord 13 of the main transverse girder of the machine frame formed in connection with the slanting stay 14 and the upper chord 16. The vertical stays 12 underneath each track 11 terminate in ribs 17 connected with the front walls 18. As shown, the lower chord 13 is slightly U-shaped. The upper chord 16 is laterally displaced in relation to the impression line in such a way that the toothed segment 19 in spite of its straight direction can pass by the same, said toothed segment driving the rack 20 provided in the middle of the type bed 9 for moving the same to and fro. The stay 14 is bulged at 21 to provide space for free movement of the toothed segment 19. The toothed segment 19 is mounted on a shaft 22 which is supported at 23 and 24 and bears outside of the side wall 25 of the machine frame a toothed segment 26 which, as shown in Fig. 3, is formed at each end with a projection 27 having a cycloidal recess 28. The toothed segment 26 engages alternately a toothed segment 29 and a toothed segment 29', said segments 29 and 29' being fastened to two oppositely rotating toothed wheels 30 or 30', respectively. At the end of each toothed segment 29, 29' is provided a roller 31, 31' for alternate engagement in the cycloidal recesses 28, whereby the movement of the toothed segment 26 on engagement of one roller and disengagement of the other roller is retarded or accelerated. Conventional means (not shown) are provided for driving the toothed wheels 30 and 30' in opposite directions, by insertion of a reversing wheel, from the driving shaft 32.

While the invention has been described in detail with respect to a now preferred example and embodiment of the invention it will be understood by those skilled in the art after understanding the invention, that various changes and modifications may be made without departing from

the spirit and scope of the invention and it is intended, therefore, to cover all such changes and modifications in the appended claims.

What is claimed is:

1. A printing press of the character described comprising a press bed, a type bed mounted on said press bed for reciprocating movement from one end to the other, tracks on said press bed for guiding and supporting said type bed during said reciprocating movement, an impression cylinder mounted transversely over said press bed intermediate the ends thereof, said impression cylinder defining an impression line of maximum pressure transversely of said press bed, a toothed rack on the bottom of said type bed substantially in the middle thereof, gear means under said press bed cooperating with said toothed rack for driving said type bed in said reciprocating motion, said gear means protruding upwardly through said press bed substantially beneath said impression cylinder, a lower transverse chord adjacent the bottom of said press bed substantially aligned with said impression line, an upper transverse chord supporting said press bed disposed to one side of said impression line, a slanting web rigidly interconnecting said lower and said upper chords and meeting said lower chord vertically below said impression line, a bulge in said web defining an operating housing for said gear means, and substantially T-shaped vertical stays disposed longitudinally of said press bed supporting said tracks on the upper portions of said stays, substantially the entire force of said stays resting on said lower chord.

2. A printing press of the character described comprising a press bed, a type bed mounted on said press bed for reciprocating movement from one end to the other, tracks on said press bed for guiding and supporting said type bed during said reciprocating movement, an impression cylinder mounted transversely over said press bed intermediate the ends thereof, said impression cylinder defining an impression line of maximum pressure transversely of said press bed, a toothed rack on the bottom of said type bed substantially in the middle thereof, gear means under said press bed cooperating with said toothed rack for driving said type bed in said reciprocating motion, said gear means protruding upwardly through said press bed and interrupting the transverse bracing thereof substantially beneath said impression cylinder, a lower transverse chord adjacent the bottom of said press bed substantially aligned with said impression line, an upper transverse chord supporting said press bed disposed to one side of said impression line, a slanting web rigidly interconnecting said upper chord with said lower chord along the portion thereof substantially beneath said impression line, and cantilevered vertical stays supporting said tracks and resting entirely on said lower chord.

3. In a cylinder printing press of the character described having a press bed, an impression cylinder, a reciprocating type bed moving on tracks on said press bed, and rack and pinion driving means for reciprocating said type bed mounted substantially in the middle of said press bed

and interrupting the transverse bracing of said bed substantially beneath said impression cylinder, the combination comprising a lower transverse chord adjacent the bottom of said printing press and substantially aligned with the pressure line at which said impression cylinder contacts said type bed, an upper transverse chord adjacent said press bed at one side of said pressure line, a rigid slanting web interconnecting said lower and said upper chords, said slanting web meeting said lower chord along a line vertically beneath said pressure line, and cantilevered vertical supports for said type bed tracks, said vertical supports being disposed longitudinally of said press bed with substantially the entire force thereof carried by said lower transverse chord.

4. In a printing press of the character described having a press bed, an impression cylinder, and a reciprocating type bed moving on tracks on said press bed and driven by drive means mounted substantially in the middle of said press bed and interrupting the transverse bracing thereof, a unitary cantilevered support for said press comprising in combination a lower transverse girder adjacent the bottom of said press and vertically beneath the axis of said impression cylinder, an upper transverse girder adjacent said press bed and disposed to one side of the axis of said impression cylinder, a diagonal supporting web interconnecting said upper girder with said lower girder along a line thereon substantially directly beneath said axis of said cylinder, and a plurality of substantially T-shaped cantilevered vertical supports for said type bed tracks disposed longitudinally of said press bed, said vertical supports and said diagonal web being carried substantially entirely by said lower transverse girder.

5. In a printing press having an impression cylinder, a reciprocating type bed mounted on a plurality of longitudinal tracks, and gear means for reciprocating said type bed and interrupting the transverse bracing of said printing press substantially beneath said impression cylinder, the combination which comprises a single lower transverse girder for supporting substantially the entire weight of said press and disposed vertically beneath the axis of said impression cylinder, an upper transverse girder longitudinally offset from the axis of said impression cylinder, a single inclined transverse web rigidly interconnecting said upper girder with said lower girder along a line substantially vertically aligned with the axis of said impression cylinder for transmitting printing forces on said bed to said lower girder directly beneath the axis of said cylinder, and a plurality of longitudinally disposed cantilevered vertical supports for said type bed tracks, each of said cantilevered supports being carried substantially entirely by said lower girder.
